UNITED STATES PATENT OFFICE.

DANIEL H. McGEOUGH, OF LAKEVIEW PARK, ONTARIO, CANADA.

CHAIR.

Application filed April 17, 1926. Serial No. 102,724.

This invention relates to upholstered chairs and more particularly to chairs of the chesterfield type, and my object is to provide a chair of this character which is comfortable, compact, neat in appearance, easily upholstered, strong and durable and yet cheap to manufacture. Another object is to so construct the chair that its upholstered parts may be easily removed for repair or 10 cleaning purposes.

I attain my objects by forming the chair of spring filled cushions removably secured to a metal frame and interlocked in the manner hereinafter more fully described and illustrated in the accompanying drawings in which

Fig. 1 is a longitudinal section of my improved chair;

Fig. 2 a cross section thereof;

Fig. 3 a plan view, partly in section, of the chair;

Fig. 4 a plan view of the metal frame of the chair with the cushions removed;

Fig. 5 a sectional detail showing the method of securing the covering to the frame; and

Fig. 6 a detail of the back frame upper member showing one of the links pivoted thereon.

In the drawings like numerals of reference indicate corresponding parts in the different figures.

The base of the chair is chiefly formed of angle iron, the vertical flange of which is bent at the corners to form the front 1, back 2 and sides 3. The horizontal flange of the angle iron is cut to form butt edges at the corners. At each corner of the base is suitably secured a ground or caster wheel of ordinary construction. The vertical portions of the said members 1, 2 and 3 form the walls of a recess, the bottom of which is formed by the horizontal flanges of the said members and by the grill 4 which is connected with the horizontal flanges.

The chair is provided with a back frame including side members 5 having their upper ends connected by a top member 6. These members are also formed of angle iron and the lower ends of the side members 5 are connected with the back and side walls 2 and 3 at the corners thereof. The side members 5 are also connected by a brace 7 which is provided with hooks 8 for a purpose which will hereinafter appear.

Side frames are also provided and each of

these includes a forward member 9 formed of angle iron and secured to a side 3 intermediate its ends. Each forward member extends upwardly from the base and has its upper end curved laterally, as indicated at 9^a. Rearwardly extending horizontal members 10 connect the upper ends of the members 9 with the side members 5 of the back frame. The members 10 are formed integral with the members 9 and are provided with supports 11 for a purpose which will herein-after appear. The side and forward members 5 and 9 are connected by side braces 12.

It will be noted that the angle iron construction of the back and side frames forms recesses in the frames which are adapted to partially receive the cushion back and arms 13 and 14 respectively.

The cushion back 13 is filled with spring filling 15 which includes inner and outer wire frames provided with inner and outer wire borders 16 and 17. The back is also provided with hair or similar filling 18 enclosed by a cover 19 which is secured to the outer border wire 17 and thus covers the sides of the spring filling 15. The wire 17 along the underside of the cushion back is adapted to be engaged by the hooks 8, and the same wire along the upper side of the cushion back is adapted to be engaged by links 20. These links are pivoted on lugs carried by one flange of the top member 6 and have their free ends provided with notches 21 adapted to receive the wire 17. By swinging 90 the links rearwardly past their centers, the upper border of the cushion back is pressed up and is held from sagging so that no gaps are formed between the member and the upper side of the cushion back. The lower 95 border is also held up in the hooks 8. To tend to prevent the upper part of the cushion back from sagging, I provide wire braces 22 having one end connected with the lower side of the outer border wire 17 and the other end connected with the upper side of the inner border wire 16. The side members 5 are provided with lugs 23 spaced from the outer flanges of the said members to form retaining members therewith to receive the 100 outer border wire 17 along its side portions.

The cushion arms 14 are constructed similarly to the back 13 and each arm is provided with spring filling 24 including inner and outer border wires 5 and 26. The upper 110 portion of outer border wire 26 is connected with the lower portion of the inner border

- wire 25 by the diagonal braces 27. The horizontal members 10 are provided with lugs 11 spaced from the outer flanges of the said members to form supports there-
 5 with. These supports are adapted to receive the outer border wire 26 along its upper portion. The outer lower corners of the spring fillings 24 are adapted to engage the side braces 12.
- 10 A box spring 29 is adapted to be received in the hereinbefore described recess formed in the base of the chair. The sides of the box spring are provided with vertical grooves 30 adapted to receive the upwardly
 15 extending members 9. This arrangement prevents the box spring from shifting longitudinally of the base and positions its front side in engagement with the inner side of the base front 1.
- 20 On the box spring 29 is supported a T-shaped seat 31. The laterally directed flanges 31^a of the seat are adapted to engage the front ends of the cushion arms 14, while the longitudinal sides 31^b are adapted
 25 to engage the inner lower corners of the cushion arms. The inner ends of the cushion arms are engaged by the sides of the cushion back 13.
- The parts of the chair are put together as
 30 follows. The spring box 29 is first placed in the base recess and the cushion arms 14 are positioned in the arm frame recesses and engaged with the lugs 28. The wire border 17 of the cushion back is engaged with the hooks
 35 8, and the same wire, along the upper end of the cushion, is positioned in the notches 21 of the links 20. The upper end of the cushion back is then pushed rearwardly into the recess in the back frame, which causes the
 40 links to swing past their centers to tend to retain the cushion back in this position and in engagement with the top member 6 of the back frame.
- Referring to Fig. 5, it will be noted that
 45 the horizontal members 10 are bound by the covering 32, which is secured thereto by loop knots passed through the opposite ends of the covering and through holes 33 formed in the members 10. The members 9, the upper
 50 parts of the side members 5, the top member 6, and the front parts of the base between the members 9 are bound in a manner similar to the members 10. The main portion 32^a of the covering is secured to the covering
 55 32 along the corner of the above mentioned members. The horizontal flanges of the base angle irons are also provided with holes through which the thread for securing the lower ends of the covering 32^a is passed.
- 60 It will be distinctly understood that the term "chair" used throughout the specification and claims includes a lounge, settee or chesterfield.
- What I claim is:
- 65 1. A chair provided with arm frames, in-
 cluding upwardly extending forward mem-
 bers; a base extending forwardly of the said
 forward members and extending laterally
 of their inner edges; a removable box spring
 70 supported on said base and provided with
 grooves in its sides to receive said arm frame
 members; arm cushions detachably secured
 to the arm frames and extending down-
 wardly with their lower ends over the box
 spring; and a T-shaped seat cushion resting
 75 on the box spring adapted to engage the
 inner sides and front ends of the arm cush-
 ions and to close the gaps between the box
 spring and the arm cushions.
2. A chair provided with arm frames in-
 cluding upwardly extending forward mem-
 bers; a base extending forwardly of the said
 forward members and extending laterally of
 their inner edges; a back frame connected to
 the base and arm frames; cushions detach-
 ably secured to the back and arm frames;
 a removable box spring supported on said
 base and provided with grooves in its sides
 to receive said arm frame members, said box
 spring extending under the lower ends of
 the arm and back cushions; and a T-shaped
 seat cushion resting on the box spring adapt-
 ed to engage the inner sides and front ends
 90 of the arm cushions and the front of the
 lower end of the back cushion to close the
 gaps between the box spring and the arm
 and back cushions.
3. A chair provided with arm frames; a
 back frame; a base extending forwardly of
 the arm frames; cushions detachably secured
 to the arm and back frames; a removable
 box spring supported on said base extending
 under the lower ends of the arm and back
 cushions; and a T-shaped cushion resting on
 the box spring adapted to engage the inner
 sides and front ends of the arm cushions and
 the front of the lower end of the back cushion
 to close the gaps between the box spring
 and the arm and back cushions.
4. A chair provided with a back frame; a
 spring filled cushion back having its rear
 side provided with a wire border; hooks on
 the back frame adapted to be engaged from
 below by the lower part of the wire border;
 fingers pivoted on the upper part of the
 frame having notches in their ends whereby
 they may be engaged beneath the upper part
 of the wire border and swung back past the
 plane intersecting their pivots and the points
 of engagement of the lower part of the bor-
 der with the hooks; and means limiting the
 backward movement of the fingers.
5. A chair having arm frames provided at
 their upper parts with upwardly facing
 hooks; a base; arm cushions provided with
 connecting means adapted to engage said
 hooks, said cushions extending downwardly
 towards the base; side rails against which
 the backs of the lower parts of the cushions
 may rest; a box cushion extending under the

lower ends of the cushions; and a seat cushion supported on the box cushion to engage between the arm cushions to retain them in position.

6. A chair provided with arm frames; a back frame; a base extending forwardly of the arm frames; cushions detachably secured to the arm and back frames; a removable box spring supported on said base extending under the lower ends of the arm and back cushions; and a seat cushion resting on the box spring adapted to engage the inner sides and front of the lower end of the back cushion to close the gaps between the box spring and the arm and back cushions.

7. A chair having arm frames provided at their upper parts with upwardly facing hooks; arm cushions each provided with a

spring filling including inner and outer border wires, said cushions curving inwardly and downwardly from the tops of the arm frames and being supported by the upper sides of their outer border wires from said hooks; a rail at each side against which the lower part of the outer border wire of the adjacent cushion may rest; diagonal braces in each cushion extending from the upper side of the outer border wire to the lower side of the inner border wire; and a seat cushion supported from the base to engage between the arm cushions to retain them in position.

Signed at Toronto, Canada, this 29th day of March, 1926.

DANIEL H. McGEOUGH.
